APPARATUS FOR CONTRACTING THE
MARGIN OF SHEET MATERIAL

Jacob S. Kamborian, West Newton, Mass.

Application March 27, 1948, Serial No. 17,506

20 Claims. (Cl. 12—51)

1

This invention pertains to apparatus for shrinking or contracting a marginal portion of a piece of normally substantially flat sheet material thereby to impart a concavo-convex effect to the material at and adjacent to said marginal portion. While of broader utility, the illustrative embodiment herein chosen for specific description is primarily intended to impart a pre-lasted shape to a shoe upper, particularly to an end portion of the shoe upper, for example to the toe end of the vamp, thereby to facilitate the attachment, as by stitching, of the upper to a bottom member, for instance a sock lining, inner sole or the like. In particular the present invention pertains to improved apparatus for practicing a method such as disclosed in the patent to Kamborian, No. 2,378,639, dated November 19, 1945, and to improvements in mechanism of the type also disclosed in said patent.

Objects of the present invention are to provide a machine of the class described which is equally useful and effective for shrinking materials of widely different characteristics and thicknesses, for instance kid, calf, crushed goat, capeskin, and elk leathers; paper; stiffened textile fabric; sheeted thermoplastic resin; or paper or cloth impregnated with resin or coated with metal-foil, or other materials. A further object is to provide a machine operative to shrink the marginal portion of sheet material with concomitant increase in the density of the marginal portion but preferably without appreciable crinkling or corrugation of the material. A further object is to provide a machine of the class described which is rugged and durable, which is easy to use and rapid in operation and having adequate provision for the lubrication of its moving parts. A further object is to provide apparatus of the class described having provision for adjusting its operative elements so as to adapt it for use in shaping materials of widely different thickness and other characteristics. A further object is to provide apparatus of the class described having provision for heating the material at the point at which it is being worked and operative to supply different degrees of heat and to apprise the operator of the degree of heat being used. A further object is to provide apparatus of the class described wherein the retarding force is applied by means of a normally stationary element. Other and further objects and advantages of the invention will be pointed out in the following more detailed description and by reference to the accompanying drawings wherein:

2

Fig. 1 is a front elevation of the machine with the front cover removed;

Fig. 2 is an elevation of the right-hand side of the machine with the side door removed, the front cover in place, and with certain parts in vertical section to show the interior construction;

Fig. 3 is a plan view of the machine with the top cover removed;

Fig. 4 is a fragmentary vertical section substantially on the line 4—4 of Fig. 3;

Fig. 5 is a fragmentary vertical section, to larger scale in the vertical plane on the line 5—5 of Fig. 3, but with many of the parts omitted;

Fig. 6 is a fragmentary front view of the machine, to larger scale than Fig. 1, and showing details of the anvil-supporting plate;

Fig. 7 is a fragmentary front elevation, partly in vertical section, showing the anvil-supporting plate, the presser foot support, and the adjustable means for moving the anvil and presser foot;

Fig. 8 is a fragmentary front elevation illustrating the cooperative action of the presser foot, anvil and work-advancing wheel upon the work;

Fig. 9 is a fragmentary vertical section substantially on the line 9—9 of Fig. 8;

Fig. 10 is a diagram of the electrical connections;

Fig. 11 is a diagrammatic plan view of a shoe vamp as it appears before being acted upon by the machine; and

Fig. 12 is a diagrammatic perspective view showing a vamp after it has been acted on by the machine.

Referring to the drawings, the numeral 1 indicates the frame or housing of the machine, conveniently a casting, although it is contemplated that it may be made of sheet metal or built up of pressed metal sections. As illustrated, the housing has base flanges 2 so designed to receive bolts for securing it to a bench or other support. The housing comprises the rear wall 3, the front wall 4, the left-hand end wall 5 and the bottom wall 6, and also includes an internal web 7 which separates a rear chamber 8 for the reception of change speed drive means from a forward gear chamber 9. This web 7, or a continuation thereof, extends down (Fig. 2) below the bottom wall 6 so that the forward chamber 9 is deeper than the rear chamber and if desired, the chamber 9 is designed to hold lubricating oil for the gears housed therein and the part 10 of the web 7 may be provided with a drain opening 11 threaded for the reception of the end of an oil drain pipe (not shown).

The right-hand side of the housing is nor-

mainly closed by a door 12 (Fig. 1) pivotally secured at its lower end at 13 to links 14 which are pivoted at their inner ends to the housing. The door is provided with a handle or knob 15 by means of which it may be manipulated. The top of the housing is normally closed by a removable cover 16.

The left-hand side wall 5 of the housing is provided (Fig. 4) with an opening leading into the lower part of the rear chamber 8. A flange 17 concentric with this opening is bolted to the wall 5, the flange being integral with an elongate housing 18 in which is journalled a drive shaft 19 having a pulley fixed to its inner end. This shaft extends outwardly through the wall 5 of the housing and is provided at its outer end with a coupling member 21 by means of which it may be connected to a drive motor (not shown). The housing 18 contains anti-friction bearings for the shaft 19.

Secured to the inner side of the rear wall 3 of the housing is a bracket 22 (Figs. 2 and 4) which supports a stub shaft 23 on which is pivoted the lower end of an upright bracket 24 having a bearing 25 at its upper end in which is journalled a shaft 26. This shaft is provided with a pulley 27 at its left-hand end. A drive belt 28 embraces the pulleys 20 and 27 so that power is thereby transmitted from the shaft 19 to the shaft 26. A cone pulley 29 is fixed to the right-hand end of the shaft 26. Preferably this cone pulley is of the multiple-groove type designed for the reception of a V-belt.

The right-hand end wall of the chamber 9 is provided with an opening which receives an elongate housing 30 (Fig. 3) integral with a flange 31 which is bolted to the outer side of the wall of the chamber 9. A shaft 31 is journalled in the housing 30, within which appropriate anti-friction bearings are arranged. One end of shaft 31 is in the chamber 9 and has a driving worm 32 fixed to it. At its right-hand end, outside of the chamber 9, the shaft 31 has fixed thereto a cone pulley 33 similar to the pulley 29, but reversed in position. An endless belt 34 embraces the pulleys 29 and 33 and transmits power from the pulley 29 to the pulley 33. By shifting this belt from one pair of grooves to another on the pulleys 29 and 33, the speed of the shaft 31 may be varied.

The bracket 24, which supports the bearing 25, is provided with a bearing opening intermediate its ends which receives a rotatable pin 35 (Fig. 2) provided with a screw threaded opening which receives a screw threaded shaft 36 passing out through an opening in the rear wall 3 of the housing and having at its rear end a handle 37. By turning the handle 37, the bracket 24 may be swung about the pin 23, thus moving the bearing 25 and varying the tension of the belt 34.

The driving worm 32 engages a worm wheel 38 (Figs. 2, 3 and 5) which is fixed to a shaft 39 journalled in a bearing sleeve 40 (Fig. 5) fitting within a bore in a boss 41 integral with the front wall 4 of the housing. The bushing 40 has an enlargement at its forward end and is held in place by a collar 42. The bushing is preferably provided with anti-friction bearings or sleeves 43 in which the shaft 39 is journalled.

The shaft 39 has a head 44 at its forward end provided with an axial bore 45 which receives the rear end of an arbor 46 which is held rigidly in place in the bore 45 by a set screw 47. This arbor 46 has a head 48 at its forward end which forms an abutment for the forward face of the toothed work-advancing wheel 49, the wheel being held fixed to the arbor 46 by a nut 50. The wheel has

teeth 51 on its peripheral edge. Desirably, the work-advancing wheel 49 is of the order of $\frac{1}{8}$ inch thick for use in pre-shaping shoe uppers, and the teeth are preferably generally similar to saw teeth, having a rake in the direction of rotation, their upper surfaces making an angle of substantially 45° with a radius through the root of the tooth. Preferably these teeth are ground off at an angle such that their cutting edges are inclined at an angle of 20° to the face of the wheel. However, these teeth do not have a set like that of an ordinary saw. While a desirable angular arrangement of these teeth has been suggested, it is to be understood that the tooth angles may be varied within substantial limits without departing from the invention or substantially reducing the efficiency of the apparatus.

A substantially horizontal work-supporting table 52 is secured to the housing at the front 20 of the machine, this table here being shown as a hollow casting having a downwardly inclined front wall 53 defining a chamber 54 beneath the table. This chamber is closed at the bottom by a plate 55 which may be of sheet metal or the like. The sloping front wall 53 of the table is provided with apertures for the reception of transparent prismatic buttons 56 and 57 (Fig. 3) and for the reception of the forward part of a switch 59 (Fig. 2), housed in the chamber 54, having an actuating handle 58 exposed at the front side of the wall 53. The bottom plate 55 is provided with an aperture for the passage of a conductor T (Fig. 1) designed to supply heating current to the anvil as hereinafter described. The rear portion of the table 52 is cut away at 61 (Fig. 2) to provide space for the reception of the anvil and other parts hereafter described.

An anvil-supporting plate or carrier 61 (Figs. 1, 6 and 7) is arranged against the front wall 4 of the machine housing, this plate being of substantial thickness and rigid and having a bearing opening 62 at its lower left-hand portion which receives a pivot member 63 (Fig. 7) by means of which the plate is secured to the front wall of the housing and is permitted to swing in a vertical plane. The plate has a large aperture 61a (Fig. 5) for the accommodation of the enlargement at the forward end of the bearing sleeve 40 and carries an anvil-supporting bracket 64 (Fig. 6) secured to its front face immediately below this opening 61a. This bracket 64 is provided with a horizontal flange 65 on which a block B of heat-insulating material is mounted. The anvil 66 rests upon the block B and is bolted to the bracket 64. The anvil is recessed at its upper forward edge to provide the horizontal work-supporting surface 67 (Fig. 9) and the vertical edge gauge surface 68. The work-supporting surface 67 is preferably approximately flush with the upper surface of table 52. As here illustrated, the anvil 66 is provided with chambers (Fig. 5) for the reception of heating units hereinafter described.

A rigid, upstanding bracket arm 70 (Fig. 7) is secured to the plate 61 near the upper left-hand corner of the latter, this bracket having an arcuate surface 71 which is engaged by a spherically curved knob 72 at one end of a sleeve 73 which slides in the casing 74. This casing may be a casting, suitably machined to provide the bore in which slides the sleeve 73, and is rigidly secured by bolts or other fastening means to the front face of the front wall 4 of the machine housing. An elongate sleeve member 75 is also arranged to slide in the bore in the casing 74, this sleeve 75 having a head 75a at its right-hand end provided with a screw-threaded bore

which receives the screw-threaded inner end portion of an adjusting shaft 77. A coiled spring 76 bears at one end against the bottom of the sleeve member 73 and at its other against the head 75^a of the sleeve 75. The screw-threaded adjusting shaft 77 extends out through a closure plate 78 at the end of the casing 74 and is provided with a fixed collar 79 preferably having a series of peripheral sockets for the reception of a spanner wrench.

An adjustable stop member 80, having screw-threaded engagement with a bracket 81 fixed to the front of the wall 4 of the housing, limits the turning of the plate 61 in a counterclockwise direction. The plate is urged in a counterclockwise direction by the spring 76. The angular position of plate 61 determines the effective height of the work-receiving surface 67 of the anvil. By turning the screw 77, the plate 61 may be swung about the pivot pin 63, thus varying the position of the anvil with reference to the axis of the crimping wheel 49.

The anvil-supporting plate 61 is provided with a screw threaded bore 82 (Fig. 6) which receives the rear end of a pivot screw 83 (Fig. 7) upon which is pivotally supported the presser foot arm 84. This arm is provided at its left-hand end with an upstanding abutment member 85 which is engaged by a spherically curved button 86 at the left-hand end of a sleeve 87 which slides in a casing 88 which is rigidly secured to the upper part of the anvil plate 61. This casing has an elongate bore which also receives a sleeve member 89, closed at its right-hand end by a plug 89^a having an axial screw threaded bore. A heavy coiled compression spring 90 is housed within the sleeve 87 with its right-hand end bearing against the end plug 89^a of the sleeve 89 and with its left-hand end normally spaced from sleeve 87. A second coiled spring 90^a, lighter and of smaller diameter than spring 90 is arranged within the latter with one end bearing against the plug 89^a and with its other end bearing against the sleeve 87.

An actuating screw 91 has screw threaded engagement with the bore in the plug 89^a and extends out through an axial bore in the end wall of the casing 88 and is provided with a knurled head 92 whereby the screw may be turned. By turning the screw, the tension of the spring 90^a may be adjusted, and the presser foot support 84 may be swung about the axis of the pivot screw 83. The casing 88 is preferably provided with an elongate slot 93 (Fig. 1), the lower margin of which may be provided with graduations, and the sleeve 89 is provided with an index mark 94 on its forward face which cooperates with the graduations to indicate the position of adjustment of the presser foot support 84.

A stop screw 95 has threaded engagement with a vertical bore 96 near the right-hand end of the member 84 and its upper end engages the lower edge of the casing 88. A second stop screw 97 engages the lower part of the bore 96 and its head may contact a stop bracket 98 fixed to the lower part of the anvil plate 61. By adjustment of the screws 95 and 97 the amount of pivotal movement of the presser foot support 84 may be determined. The member 84 is provided with a pin 99 (Fig. 1) at its lower right-hand part and to this pin is connected the upper end of a chain 100 which extends down to an actuating treadle (not shown). By actuation of the treadle the lower end of the member 84 may be swung downwardly, thus raising its left-hand end rela-

tively to the anvil to facilitate introduction of the work.

Near its left-hand end the member 84 (Fig. 5) is provided with a forwardly directed flange 101 to which is bolted the upper horizontal arm 102 of a work retarder or presser foot 103 of substantially L-shape. The lower part of the downwardly-directed leg of this presser foot is rearwardly deflected so that its lower edge is closely adjacent to the front face of wheel 49. The presser foot has teeth 105 in its lower edge. The presser foot is desirably of the order of $\frac{1}{16}$ of an inch thick for use on shoe uppers, preferably of hard chromium steel, and the teeth preferably are sloped so that the angle between adjacent teeth is approximately 90°. Preferably the points of the teeth are substantially parallel to the work-contacting surface of the anvil and are slightly blunted so that they do not have any cutting action on the work. The right-hand tooth 105^a is spaced to the left of the vertical plane of the axis of the shaft 39 which carries the crimping wheel 49. Thus the point of closest approach of the tips of the teeth 51 of the crimping wheel to the upper surface 67 of the anvil is spaced to the right (Fig. 8) from the tip of the tooth 105^a, this spacing being approximately $\frac{1}{8}$ of an inch in the machine as actually constructed.

The two heating units 107 and 108 which are housed in the anvil are in circuit respectively with lamps 109 and 110 (Fig. 10) arranged in the chamber 54 beneath the work-supporting table, the lamps being located directly behind the transparent buttons 56 and 57 respectively. The switch 59 is of the three-way, snap type so designed that in one position no current is supplied to the heating units or lamps; in a second position current is supplied to one lamp and the corresponding heating unit, and in the third position current is supplied to both heating units and to both lamps.

To the forward edge of the flange 101 (Fig. 1) there is secured a member 106 slotted to permit horizontal adjustment and this member carries a curved guard 106^a which extends down over the right-hand edge portion of the crimping wheel 49 and which prevents premature contact of the work with the teeth of the wheel.

Before starting work, the anvil will have been adjusted to the proper height by turning the screw 77 thus compressing the spring 76 and swinging the plate 61 in a counterclockwise direction. The operator will also turn the switch 58 so as to energize both of the heating units 107 and 108, thereby quickly to bring the anvil to the proper temperature. After the anvil has thus received its preliminary heating, the switch 58 may be turned so as to cut off one of the heating units, the lamps 109 and 110 indicating to the operator whether one or both heating units is being energized. Having performed these preliminary operations, the operator places his foot on the treadle, thus swinging the presser-foot arm 84 in a clockwise direction, thereby lifting the presser foot 103 away from the anvil sufficiently to allow the edge of the vamp material V to be introduced between the presser foot and the anvil. The pressure on the treadle is now released and the anvil-carrying arm 84 is swung in a counterclockwise direction by the action of one or both of the springs 90 and 90^a. The pressure exerted by the anvil upon the work is regulated by turning the head 92 therein. When moderate pressure is desired only the spring 90^a may act upon the anvil arm but when heavy pres-

sure is desired, the head 92 may be turned sufficiently to cause both of the springs 90 and 90^a to act upon the anvil arm.

It is assumed that the drive shaft 49 is in operation, thus turning the shaft 39 which carries the work-advancing wheel 49. The teeth of this wheel bite into the material of the vamp V and tend to advance the material at the same rate as that of the teeth of the wheel. However, the movement of the vamp material is obstructed by the teeth 105 of the presser-foot, the presser-foot being fixed, and thus the material of the vamp is crowded forwardly in its own plane by the teeth of the wheel and is thus made more dense, and, in some instances, to some extent, thickened. If desired, the material of the vamp may be milled or otherwise treated to make it more plastic before it is subjected to the action of the machine. As the anvil is heated the material of the vamp is subjected to substantial heat while crowded between the anvil and the teeth of the presser-foot and thus tends to take a permanent set. Since the action of the machine is to crowd together and densify the material at the edge of the vamp, the result is to shorten the edge, and as the edge takes a permanent set in this shortened condition, the result is to produce a convexity of the marginal portion of the vamp, as illustrated in Fig. 12, thus imparting to the toe portion of the vamp a curved contour more or less similar to that of the contour of the portion of a last upon which the shoe will be lasted.

In accordance with the thickness and character of the material being operated upon, the height of the anvil will be varied and also the pressure which the presser-foot exerts upon the work. Experience may indicate the proper adjustment of these parts, but when operating upon new and untried material some experimentation may be required to determine the proper adjustment in order to secure the optimum effects.

In dealing with some materials the increased density of the material, resultant from the action of the machine, is accompanied by an increase in thickness and in other cases by a decrease in thickness, but the edge of the material is not appreciably crinkled or caused to undulate.

The continuously rotating work-advancing wheel 49 is preferable as a means for advancing the work and crowding it between the anvil and the presser-foot, but it is probable that other work-advancing means may be employed, for example a reciprocating part or parts having work-engaging teeth, and which would be advanced in the work-impelling direction by suitable means, for example, means similar to the so-called four-motion feed of a sewing machine.

The machine is very useful in pre-shaping shoe uppers, but is likewise applicable to other industries. For example, it is of value in shaping material, for instance leather, in the manufacture of handbags, in particular to shape the material bordering the opening of the bag; and in general in the manufacture of leather novelties or in upholstery, or wherever it is desirable to impart to the marginal portion of leather or like sheet material a concave contour.

While a desirable embodiment of the invention has been illustrated, it is to be understood that variations in the shape and arrangements of parts and substitution of equivalents are to be regarded as within the scope of the invention.

I claim:

1. Apparatus of the class described comprising a housing having a substantially vertical front wall, an anvil support pivotally secured to said

front wall to swing in a vertical plane, an anvil mounted at the front of said support, means for swinging the support thereby to adjust the anvil vertically, a driven work-advancing wheel turning about an axis perpendicular to the front wall of the housing and with its peripheral edge adjacent to the upper surface of the anvil, an adjustable presser foot support carried by the anvil support, a presser foot mounted on the presser foot support, the presser foot having a toothed work-engaging edge disposed above and adjacent to the anvil, means resiliently urging the presser foot support in a direction to contact the presser foot with the anvil, adjustable stop means to limit said movement of the presser foot support, and means operative to move the presser foot support in a direction to separate the presser foot from the anvil.

2. Apparatus of the class described comprising a housing having a substantially vertical front wall, an anvil support pivotally secured to said front wall to swing in a vertical plane, an anvil mounted at the front of said support, a casing fixed to the front wall of the housing, said casing having an elongate bore, a thrust element sliding in said bore and which engages a fixed upstanding abutment member carried by the anvil support, a spring within the bore in said casing which constantly urges the thrust element in a direction such as to elevate the anvil, means for varying the tension of said spring, and an adjustable stop to limit anvil elevating movement of the support.

3. Apparatus of the class described comprising a housing having a substantially vertical front wall, an anvil support pivotally secured to said front wall to swing in a vertical plane, an anvil mounted at the front of said support, means for swinging the support thereby to adjust the anvil vertically, a peripherally toothed work-advancing wheel turning about an axis perpendicular to the front wall of the housing and with its peripheral edge adjacent to the work-contacting surface of the anvil, a presser foot lever pivotally mounted on the anvil support, the lever having a forwardly directed flange, a presser foot fixed to said flange, said presser foot having a toothed lower edge disposed close to the front face of the work-advancing wheel and closely adjacent to the anvil, adjustable means tending resiliently to turn the presser foot support in a direction to contact the toothed edge of the presser foot with the anvil, and adjustable means for limiting such movement.

4. Apparatus for use in shrinking the margin of sheet material, said apparatus comprising a positively driven toothed wheel so arranged that its teeth bite into the material and apply a positive advancing force to the material close to the edge of the latter, and a non-rotatable retarding element constructed and arranged to engage the material at a point spaced forwardly, in the direction of work advance, from the point at which the toothed wheel applies the maximum advancing force, a normally fixed anvil for supporting the material as it is advanced by the wheel, and means for heating the anvil.

5. Apparatus for use in shrinking the margin of sheet material, said apparatus comprising a positively driven toothed wheel so arranged that its teeth bite into the material and apply a positive advancing force to the material close to the edge of the latter, a non-rotatable retarding element constructed and arranged to engage the material at a point spaced forwardly in the direction of work advance from the point at which

the path of the tooth tips of the wheel is tangent to the work, a normally fixed anvil for supporting the material as it is advanced by the wheel, and means for heating the anvil.

6. Apparatus of the class described comprising a work-supporting table having a substantially horizontal surface, an anvil having a work-contacting face which is substantially flush with the horizontal surface of the table and a substantially vertical surface for guiding the work, a 10 peripherally toothed work-advancing wheel turning in a plane substantially parallel to said guide surface and having one face closely adjacent to said guide surface, a nonrotatable work-retarding element adjacent to the opposite face of the 15 wheel and having a work-engaging edge, the periphery of the wheel and the work-engaging edge of the retarding element being toothed and closely adjacent to the work-supporting face of the anvil at the working point, and heating 20 means for the anvil.

7. Apparatus for use in shrinking the margin of sheet material, said apparatus comprising a positively driven toothed wheel so arranged that its teeth bite into the material and apply a positive advancing force to the material close to the edge of the latter, a normally fixed anvil for supporting the material as it is advanced by the wheel, a normally fixed retarding element constructed and arranged to engage the material at a point spaced forwardly in the direction of work advance from the point at which the path of the tooth tips of the wheel is most nearly tangent to the anvil, a lever constituting a support for the retarding element, adjustable means tending to swing the lever so as to move the retarding element toward the anvil, adjustable stop means for limiting such movement of the lever, and means for swinging the lever in the opposite direction to separate the retarding means from the anvil, thereby to facilitate introduction of the material between the anvil and retarding element.

8. Apparatus for use in shrinking the margin of sheet material, said apparatus comprising a positively driven toothed wheel so arranged that its teeth bite into the material and apply a positive advancing force to the material close to the edge of the latter, a normally fixed anvil for supporting the material as it is advanced by the wheel, a normally fixed retarding element constructed and arranged to engage the material at a point spaced forwardly in the direction of work advance from a radius of the toothed wheel which is perpendicular to the anvil, a lever constituting a support for the retarding element, the retarding element consisting of a rigid member having a toothed lower edge engageable with the material, the points of the teeth of said retarding member being in a plane substantially parallel to the work-contacting face of the anvil, resilient means urging the lever in a direction to contact the retarding element with the anvil, and stop means operative to limit such movement.

9. Apparatus of the class described comprising a driven peripherally toothed work-advancing wheel, an anvil having a work-engaging surface disposed adjacent to the toothed edge of the wheel, a pivoted presser foot support, a presser foot mounted on the support, said presser foot having a toothed edge disposed adjacent to the anvil and in a plane substantially parallel to the plane of the work-advancing wheel, a 10 slidable thrust element engaging a part of said presser foot support, a spring urging said thrust element

in a direction to move the presser foot toward the anvil, means for adjusting the tension of the spring, and adjustable stop means operative to limit movement of the presser foot support by said spring.

10. Apparatus of the class described comprising a driven peripherally toothed work-advancing wheel, an anvil having a work-engaging surface disposed adjacent to the toothed edge of the wheel, a pivoted presser foot support, a presser foot mounted on the support, said presser foot having an edge disposed adjacent to the anvil and in a plane substantially parallel to the plane of the work-advancing wheel, said edge having teeth which are dulled at their tips, a 15 slidable thrust element engaging a part of said presser foot support, a compound spring urging said thrust element in a direction to move the presser foot toward the anvil, means for adjusting the tension of the spring, adjustable means operative to limit movement of the presser foot support in either direction, and means for moving the presser foot away from the anvil.

11. Apparatus of the class described comprising a housing, a work-supporting anvil arranged externally of the housing, a peripherally toothed work-advancing wheel having its edge adjacent to the work-contacting surface of the anvil, the edges of the teeth extending diagonally across the width of the wheel, a nonrotatable work retarder having a toothed work-engaging edge adjacent to the work-contacting surface of the anvil, means supporting the work retarder for movement toward and from the anvil, the first tooth of the work retarder with which the advancing work contacts being spaced in the direction of work advance from the point of maximum application of the work advancing force.

12. Apparatus of the class described comprising a housing, a work-supporting anvil arranged externally of the housing, a peripherally toothed work-advancing wheel having its edge adjacent to the work contacting surface of the anvil, a presser foot support, a non-rotatable presser foot, means fixing the presser foot to the presser foot support, the presser foot having a series of work-engaging teeth at its edge, the points of said teeth being in a plane substantially parallel to the work-contacting surface of the anvil, the first of said teeth to engage the work being spaced, in the direction of work advance, from the point at which the periphery of the work-advancing wheel most nearly approaches the anvil.

13. Apparatus of the class described comprising a housing, a work-supporting anvil arranged externally of the housing, a peripherally toothed work-advancing wheel having its edge adjacent to the work-contacting surface of the anvil, said work-advancing wheel being of the order of $1/16$ inch thick, the teeth of the wheel having a rake in the forward direction of rotation, a normally fixed presser foot, of the order of $1/16$ inch thick, disposed closely adjacent to the front face of the wheel, said presser foot being of hard wear-resistant material and having a toothed edge adjacent to the work-contacting face of the anvil, the points of the presser foot teeth being in a plane substantially parallel to the surface of the anvil, the first presser foot tooth to be contacted by the work being spaced, in the direction of work advance, from the point of nearest approach of the wheel to the anvil, and means for moving the presser foot away from the anvil to facilitate the entry of work.

14. Apparatus of the class described comprising a rigid anvil for supporting the material to be operated on, a driven peripherally toothed wheel having its toothed edge arranged closely adjacent to the work-supporting surface of the anvil, a normally fixed work-retarding element of substantially inverted L-shape, a support for the work-retarding element, means securing the horizontal leg of the work-retarding element to said support, the downwardly-directed leg of the work-retarding element being disposed closely adjacent to the wheel, said retarding element having a work-engaging edge adjacent to the work-supporting surface of the anvil, said work-engaging edge of the retarding element being so designed and arranged that its first point of contact with the advancing work is spaced in the direction of work advance from the point of nearest approach of the wheel to the anvil, and resilient means operative to urge the work-retarding element against the material.

15. Apparatus of the class described comprising a rigid anvil for supporting the material to be operated on, a driven, peripherally toothed wheel having its toothed edge arranged closely adjacent to the work-supporting surface of the anvil, a normally fixed work-retarding element closely adjacent to the wheel, said retarding element having a toothed work-engaging edge adjacent to the work-supporting surface of the anvil, said work-engaging edge of the retarding element being so designed and arranged that its first point of contact with the advancing work is spaced in the direction of work advance from the point of nearest approach of the wheel to the anvil, resilient means urging the retarding element toward the anvil, and stop means for limiting approach of the retarding element toward the anvil.

16. Apparatus of the class described comprising a rigid anvil for supporting the material to be operated on, a driven, work advancing wheel having its edge arranged closely adjacent to the work-supporting surface of the anvil, a normally fixed work-retarding element closely adjacent to the wheel, said retarding element having a toothed work-engaging edge adjacent to the work-supporting surface of the anvil, said work-engaging edge of the retarding element being so designed and arranged that its first point of contact with the advancing work is spaced in the direction of the work advance from the point of nearest approach of the wheel to the anvil, adjustable resilient means urging the retarding element toward the anvil, stop means to limit movement of the retarding means toward the anvil, and means operative to adjust the anvil toward and from the edge of the wheel.

17. Apparatus of the class described comprising a work-supporting table, an anvil having a work-contacting face which is substantially flush with the upper surface of the table and a surface for guiding the work, a peripherally toothed work-advancing wheel turning in a plane substantially parallel to said guide surface and having one face closely adjacent to said guide surface, a normally stationary work-retarding ele-

ment adjacent to the opposite face of the wheel and having a work-engaging edge, the periphery of the wheel and the work-engaging edge of the retarding element being closely adjacent to the work-supporting face of the anvil at the working point, and a guard partially encircling the wheel at that side from which the work approaches the wheel.

18. Apparatus of the class described comprising an anvil having a substantially horizontal work-contacting face and a substantially vertical surface for guiding the work, a peripherally toothed work-advancing wheel having one face closely adjacent to said guide surface, a normally stationary work-retarding element adjacent to the opposite face of the wheel and having a work-engaging edge, the periphery of the wheel and the work-engaging edge of the retarding element being closely adjacent to the work-supporting face of the anvil at the working point, means for adjusting the anvil and retarding element simultaneously with reference to the axis of the wheel, and means for adjusting the retarding element relatively to the anvil.

19. A machine of the class described comprising a housing having spaced front and rear walls, a bottom wall, and means within the housing dividing its interior into front and rear chambers, a power delivery shaft within the rear chamber, a driven shaft within the rear chamber, said latter shaft being supported for bodily movement in a direction transverse of its axis, a belt for conveying power from the drive shaft to the driven shaft, a pulley on the driven shaft, a worm shaft carrying a worm and pulley, a belt embracing the two pulleys, means for moving the driven shaft bodily to tension said belt, a worm wheel driven by the worm shaft, the worm wheel having a shaft, and a work-advancing wheel fixed to the shaft of the worm wheel.

20. Apparatus for use in shrinking the margin of sheet material, said apparatus comprising a positively driven toothed wheel so arranged that its teeth bite into the material and apply a positive advancing force to the material close to the edge of the latter, and a normally fixed retarding element, a support for the retarding element, said support being normally stationary, means fixedly securing the retarding element to said support, said retarding element being constructed and arranged to engage the material at a point spaced forwardly, in the direction of work advance, from the point at which the toothed wheel applies the maximum advancing force, a normally fixed anvil for supporting the material as it is advanced by the wheel, and means for heating the material while it is in contact with the toothed wheel.
